ROLLING MILL DRIVE AND CONTROL
SYSTEM

Alonzo F. Kenyon, Wilkinsburg, and Willard G. Cook, Forest Hills, Pa., assignors to Westinghouse Electric & Manufacturing Company, East Pittsburgh, Pa., a corporation of Pennsylvania

Application January 3, 1934, Serial No. 705,073

38 Claims. (Cl. 80—32)

Our invention relates, generally, to electric drives and control systems for rolling mills and more particularly to an electric drive and control system for driving and controlling the operation of a cold roll mill having a reel on each side of the main roll stand, commonly known as a single stand reversible mill.

During the past few years, notable advances have been made in the design of cold roll mills of the above type making it possible to roll at very high speeds as compared to the speeds obtained on the older mills.

The increased speed of rolling thin strip material has made it necessary to provide electric drives and control systems for these mills of such nature that the high speeds be readily obtainable and that the mill motor and reel motors be so controlled as to accurately control both the entry and wind-up tensions under all conditions regardless of speed, thickness of the material being rolled and the reduction being made on each pass. The tension control must so operate as to maintain the proper tension under conditions of acceleration and deceleration and must also be capable of easy and ready adjustment to change the tensions when desired.

The control in general must be flexible in operation and provide for effecting the operation of the reel motors individually to set-up the mill and thereafter maintain tension or for effecting the operation of one reel motor and the main mill motor or to control all of the motors in unison from any one of two operating stations during the rolling operations when the strip material is being unwound from the entry reel under tension, passed through the rolls and rewound under tension on the wind-up reel and the operation reversed and repeated until the desired reduction is made.

The object of our invention, generally stated, is to provide an electric drive for a rolling mill which shall be simple and efficient in operation and which may be economically manufactured and installed.

A more specific object of our invention is to provide for driving electrically a rolling mill comprising a roll stand and winding reels on either side of the roll stand, in either direction, or successively in opposite directions and automatically maintaining a predetermined constant tension on the metal as it enters and leaves the roll stand.

Another object of our invention is to provide, in an electric mill drive of the hereinbefore described character, for maintaining substantially the same winding and unwinding tensions on the

metal during periods of acceleration and deceleration as during constant speed operation of the mill.

A further object of our invention is to provide for operating the mill over any one of several speed ranges and for preventing a change from one speed range to another unless the mill is stopped.

A still further object of our invention is to provide for controlling the operation of a mill of the above-described character from any one of a plurality of control stations, for selecting the direction of operation of the mill and for rendering only one control station effective dependent upon the direction selected.

Another object of our invention is to provide for utilizing a booster generator in conjunction with the motor on either of the two reels which is functioning as the unwinding reel in order that the reel motor may function as a drag generator and return energy to the supply circuit without developing full line voltage and also that it may be required to develop only a low voltage at slow speed.

Another object of our invention is to provide for the use of current regulators to cause the reel motors or generators, whichever they may be, to maintain substantially constant tension on both sides of the mill and for automatically recalibrating the regulators dependent upon the speed range selected and during periods of acceleration and deceleration of the mill.

A still further object of our invention is to provide for causing the current regulators to maintain substantially constant entry and wind-up tensions regardless of whether or not the reel motors may change from generators to motors or vice versa during periods of acceleration and deceleration of the mill.

Other objects of our invention will become apparent from the following detailed description of its structural and operating features and the drawings, in which

Figures 1 to 6, inclusive, when placed together side to side form the complete diagram of the electric drive and control system of our invention.

In practicing the invention, the main mill motor receives power from a generator and its speed and direction of operation are controlled by varying the amount and direction of the generator voltage.

A motor is provided for each reel which alternately functions as a motor or a generator dependent upon the direction of the pass, i. e. from left to right or right to left. During the odd

passes i. e. the first, third, fifth, etc., the reel motor on the entry side of the mill functions as a drag generator to subject the metal to a back tension while the motor on the wind-up side functions as a motor to subject the metal to a pulling tension.

The drag generator is disposed to be connected across the main generator circuit in series with a main booster generator while the motor of the wind-up side is disposed to be connected directly across the generator circuit. The main booster generator is always connected in series with whichever motor is acting as the drag generator and suitable switches are provided for establishing the proper connections.

The main booster is provided with separately excited main and auxiliary field windings, the auxiliary field winding being connected across the exciter circuit by reversing contactors and the main field winding is connected across the main generator circuit so that its excitation both as to direction and amount is dependent upon the generator voltage.

The excitation of the reel motors is controlled by booster exciter generators having their armatures connected in series with the reel motor field windings, respectively, across the excitation circuit. The excitation of the booster excitors is controlled by current regulators responsive to the load currents flowing in the reel motor circuits. One regulator is always used on the entry side and the other on the wind-up side and suitable switches are provided for shifting from one reel motor circuit to the other dependent upon the direction of the pass through the mill.

The regulators may be adjusted to maintain any desired current in the reel motor circuits corresponding to the tensions desired by varying the resistance of their coil circuits. Provision is also made to change the resistance of the coil circuits dependent upon the speed range in which the mill is to operate and also when it is desired to accelerate or decelerate.

The mill is accelerated or decelerated by varying the main generator voltage through the operation of a motor-operated rheostat controlling the excitation of the generator. Whenever the motor-operated rheostat is functioning to vary the generator voltage to accelerate the mill, the resistance of the regulator coil circuit on the delivery reel motor is increased so that an additional amount of current may flow in the delivery reel motor circuit to accelerate the reel while still maintaining the necessary amount of current for constant tension. During this time, the resistance of the regulator coil circuit on the entry side controlling the drag generator is decreased in order to reduce the generator torque sufficiently to compensate for the extra pull or tension placed on the strip by the main mill to accelerate the generator to the higher speeds.

During periods of deceleration, the resistances of the regulator coil circuits are changed in the reverse order since in this case the inertia of the reel and motor on the wind-up side tend to increase the tension while on the entry side the inertia of the reel and drag generator tend to reduce the tension.

The direction of the pass through the mill is controlled by a pass selector master switch located on one side of the mill stand such, for example, as at the left control desk. The operation of this switch to its "left" position connects the generator field in the proper direction and operates certain relays to connect the regulators to the

proper reel motor circuits and booster exciter fields for the odd numbered passes while its operation to the "right" position establishes the necessary circuit setups for the even passes.

The actual operation of the mill is controlled by means of speed selector, main, reel and mill master switches, and inch, tension and release tension push buttons, located on both sides of the mill stand, thus forming two similar control stations, either of which is effective dependent upon the position of the pass selector master switch.

The speed selector master switches function to make all the necessary circuit set-ups for the desired speed range. That is, by their operation, the proper amount of resistance is inserted in the regulator coil circuits to maintain constant tension throughout the selected speed range, the proper circuits are established for changing the resistance of the regulator coil circuits during periods of acceleration and deceleration and the proper resistance is placed in the mill motor shunt field circuit, the reel motor shunt field circuits, the main booster generator auxiliary and main field circuits, and the booster exciter field circuits.

The main master switches function in one position to release the brakes on the reels, to connect the mill motor to the generator circuit, and to establish the reel motor circuits. In another position, these switches cause the motor-operated rheostat to raise the generator voltage and in another position to stop and hold the rheostat at any desired position. These masters also have a stop position which stops the mill with the strip under tension.

The reel master switches control the reel motors individually when it is desired to position the reel for any reason. Likewise, the mill master switches control the mill motor separately of the reel motors.

Referring now to the drawings, and particularly to Fig. 1, there is illustrated diagrammatically a mill of the kind for which the present invention is particularly adapted, which comprises a roll stand 10 and right and left reels 11 and 12, respectively. The reels 11 and 12 are provided with electro-magnetic brakes 13 and 14, respectively. The roll stand 10 may be driven by a suitable direct current motor 15 through suitable gearing 16 in a well known manner. Likewise, the reels may be driven or braked by means of direct current motors 17 and 18 connected through gears as shown.

Power may be supplied to the mill motor 15 and reel motors 17 and 18 by a direct current generator 19, provided with a field winding 21, which may be driven in any suitable manner, such as by a synchronous or other constant speed motor.

In the operation of mills of this type, it is desirable to operate the mill over a wide speed range of possibly from 125 to 250 R. P. M. to provide a delivery speed of from 500 to 1000 feet per minute if the mill working roll diameter is around 16 inches. Then, assuming that the reel drums are about 30 inches in diameter when empty and the coil of strip may build up to 48 inches in diameter and that reductions up to 50% per pass are desired, the entry or unwinding reel must operate over a speed range of from 20 to 125 R. P. M.

This is a 6 to 1 ratio and since it is impractical to build large capacity direct current motors to operate over such a wide speed range by shunt field control, a main booster generator 22 is provided and connected in series with whichever one

of the reel motors that is functioning as a drag generator to the generator circuit in order that the drag generator will only be required to develop a low voltage at low speeds, this voltage being increased by the main booster generator to a value such as to feed back into the main generator circuit. The main booster generator 22 may be driven in any suitable manner.

As shown, the main booster generator 22 is provided with a main field winding 23 disposed to be excited from the generator 19 and, therefore, vary the voltage of the booster generator in accordance with the mill speed. The booster generator 22 is also provided with an auxiliary field winding 24 which is utilized to control the booster generator voltage for inching operations on the entry reel preparatory to threading the metal through the mill stand and also for establishing back tension before the main generator voltage is raised to a high value.

As shown, the main booster generator 22 has one armature terminal connected directly to the generator bus 25 through a resistor 26. In order to provide for connecting the opposite terminal 25 of the main booster generator in series with either reel motor switches 27 and 30 are provided. The reel motor circuits may be completed by means of switches 29 and 38, which connect the opposite terminals of the reel motor armatures to the opposite generator bus 31. Switches 32 and 33 are provided for connecting the reel motor armatures directly to the generator bus 25.

When it is desired to roll from right to left, reel 11 becomes the entry reel and subjects the 35 un winding strip to a back tension. Therefore, switches 27 and 28 are closed to connect the main booster generator 22 in series with the reel motor 11, which now operates as a generator, across the generator busses 25 and 31. For this direction of 40 rolling, reel 12 becomes the wind-up reel and switches 29 and 33 are closed to connect the reel motor 18 directly across the generator busses 25 and 31.

Hereinafter, the pass through the mill from 45 right to left, as viewed in Fig. 1, will be referred to as the "odd" pass, whereas the pass in the opposite direction will be the "even" pass. The first pass through the mill is, of course, the first "odd" pass. Each time the direction of pass is 50 reversed, the reel which was formerly the entry reel becomes the wind-up reel and the other reel becomes the entry reel.

A switch 34 is provided for connecting the mill motor 15 to the generator. The mill motor is 55 provided with a dynamic braking resistor 35 which may be connected across the armature by means of a switch 36 in a well known manner.

In order to provide for maintaining the desired tension on the strip material, provision is 60 made for controlling the excitation of the reel motors in such manner as to maintain a constant armature current corresponding to the desired tension. In this embodiment of the invention, the field windings 37 and 38 of reel motors 11 and 18, respectively, are connected in series with the armatures of auxiliary booster excitors 39 and 40, respectively, across the source of excitation, as shown in Fig. 4.

In making the drawings, it has been deemed 70 advisable in the interests of simplicity, to carry many of the circuits through cables 41 and 42. In order to identify the circuits extending through the cables 41 and 42, the points of entry and exit of the conductors will be designated by like letters. The connections from the booster excitors

in Fig. 4 are carried through the cable 41 to the reel motor field windings in Fig. 1.

A source of constant potential voltage for furnishing excitation current to the various machines and operating currents for the relays is provided in the form of a generator 43, Fig. 1, which may be connected to supply conductors X and Y which extend on either side of the diagram.

The voltages of the booster excitors 39 and 40 are varied to control the excitation voltages impressed upon the field windings of the reel motors, by means of current regulators 44 and 45, respectively, shown in Figs. 2 and 3.

The current regulators 44 and 45 may be of any suitable type. The particular kind illustrated are well known in the art and will not be described in detail other than to state that in the case of regulator 44 which is always used on the wind-up side of the mill, it comprises generally a core 46, provided with a magnetizing winding 47, an anti-hunt winding 48 and a movable coil 49 which actuates the movable contacts 51 in such manner as to alternately increase and decrease the effect of the resistors 52 to 55, inclusive, which are connected in circuit across the excitation source with whichever one of the booster exciter fields that is associated with the wind-up reel motor. In other words, the regulators are alternately connected to opposite booster exciter fields as the direction of operation of the mill is reversed.

The regulator 45, which is always used to control the booster exciter associated with the entry reel motor, also comprises a core 56, a magnetizing winding 57, an anti-hunt winding 58 and a movable coil 59 which actuates the movable contacts 61 to vary the effectiveness of the resistors 62 to 65, exactly in the same manner as in the case of regulator 44.

The moving coils 49 and 59 of the regulators 40 are disposed to be energized in accordance with the load currents of the reel motors or generators to hold these currents and, therefore, the strip tension at a constant value at all times.

The connections of the coils 49 and 59 and the regulator contacts 51 and 61 to the proper reel motor circuits and booster exciter field windings, are controlled by a set-up relay 66, which when deenergized, connects the moving coil of the entry regulator 45 across the resistor 26, Fig. 1, in the main booster generator circuit so as to be energized in the proper direction when the mill is operating in one direction, and which, when energized, reverses the coil connection. The set-up relay 66, when deenergized, also connects the moving coil of the wind-up side regulator 44 across a resistor 67 in the armature circuit of the right reel motor, and when energized switches this connection to a similar resistor 68 in the armature circuit of the left reel motor.

The set-up relay 66, when deenergized also connects the contacts of the entry side regulator 45 to the booster exciter field associated with the entry reel motor and the contacts of the wind-up side regulator to the opposite booster exciter field. 65 When the relay is energized, the foregoing contact connections are reversed. This set-up relay has other functions in connection with making the proper circuit set-ups depending on the direction of pass as will appear as the description proceeds.

As will be readily understood, the regulators 44 and 45 may be caused to maintain predetermined constant armature currents in the machines to which they are connected, depending upon the resistances of their movable coil circuits.

In order that the resistances of the regulator coil circuits may be controlled in such manner as to always maintain the desired constant tension on the strip regardless of whether or not the mill is operating in one speed range or another, and at low or high speed in any speed range, and accelerating or decelerating under any condition, resistors 69 and 69a bias batteries 70 and 70a, tension adjusting resistances 11, 11a and 12, 12a and compensating switches 74 to 77, inclusive, are provided.

In the case of the wind-up side regulator 44, the resistor 69 is disposed to be connected in series with the coil 49, bias battery 70 and either one of the tension adjusting resistors 11 and 11a across either one of the resistors 67 and 68 in the reel motor circuits depending upon the position of the set-up switch 66. The resistors 11 and 11a are utilized to adjust the regulator coil circuit to maintain any desired tension on the strip during constant speed operation, resistor 11 being effective on the "odd" numbered passes and resistor 11a on the "even" numbered passes.

In the case of the entry side regulator 45, the resistor 69a is disposed to be connected in series with the coil 59, bias battery 70a and either one of the tension adjusting resistors 12 and 12a across the resistor 26 in the main booster generator circuit. The connection is made to resistor 26 through the tension adjusting rheostat 72 for the odd passes and reversed through resistor 72a for the even passes.

It will be apparent that when the mill is accelerated or decelerated, the regulator coil circuits must be changed or compensated accordingly. That is, when the mill is being accelerated, the wind-up reel motor must develop additional torque to overcome its own inertia and that of the reel to which it is connected, and at the same time develop sufficient torque to maintain the desired constant strip tension. This requires that the wind-up reel motor be caused to draw more current and, therefore, the regulator coil circuit must be readjusted in order to permit this additional current to flow.

In the case of the entry reel under accelerating conditions, the situation is reversed as the inertia of the drag generator and the reel increases the strip tension and, therefore, the current flowing in the generator armature must be reduced sufficiently to still maintain the strip tension constant. In this instance, the regulator coil circuit must be readjusted to cause the regulator associated with the entry reel generator to reduce its excitation.

It will be readily understood that in the case of deceleration, the readjustments of the regulator coil circuits must be made in the opposite manner as the inertia forces during deceleration are working in the opposite way.

This readjustment or compensation of the regulators during the accelerating and decelerating periods is effected in this instance by varying the effectiveness of the resistors 69 and 69a, which is accomplished by means of compensating switches 74 to 77, inclusive.

Before describing the operation of the compensating switch, it should be observed that the regulators must also be readjusted or compensated for different mill speeds. That is, the mill may operate, as will be described more fully hereinafter, within any one of a plurality of ranges, the low speed range resulting with full field excitation of the mill motor and the high speed range

resulting when the mill motor is operating on weak field.

In this instance, the compensating switches 74 and 76 are effective in the low speed range while switches 75 and 77 are effective in the high speed range only. The operation of switches 74 to 77 is controlled by suitable time delay relays 78 and 79, relay 78 being used under conditions of acceleration while relay 79 is for deceleration. Since these time delay relays are of well known construction, they will not be described in detail other than to state that they are provided with neutralizing coils 81 and 82 connected in series across conductors X and Y as shown and magnetizing coils 83 and 34, which when energized, operate the relay contacts 85 and 86 to the opposite positions from that shown.

As to whether or not the relay 78 operates switch 74 or 75 depends upon the position of the speed range switches 87 and 88, the switch 87 being closed when operating on low speed range and switch 88 being closed when operating on high speed range. These switches also determine which one of switches 76 and 77 is responsive to the operation of the time delay relay 79.

As will appear more clearly hereinafter, during constant speed operation in the low speed range, for example, the compensating switch 74 will be energized to open its contact members 74a and close contact members 74b which places a certain amount of resistance in the coil circuit of the regulator 45 and shorts a portion of the resistance in the coil circuit of regulator 44. These resistance values being such as to maintain a desired constant tension at constant speed.

When the mill is accelerated, the time delay relay 78 is caused to open its contact members 85 to deenergize the compensating switch 74 which closes its contact member 74a to reduce the resistance of the regulator coil circuit 45 and to increase the resistance of the coil circuit of the regulator 44, which, as described hereinbefore, readjusts the regulator settings to compensate for the inertia forces in the reels and reel motors. In this instance, the resistance change of the regulator coil circuits is made in one step. However, it is evident that as many steps as desired may be made.

When the mill is running at constant speed and is then decelerated, the time delay relay 79 is operated to effect the operation of switch 76, which opens its contact members 76a to further increase the resistance of the coil circuit of the entry regulator 45 and closes its contact member 76b to further decrease the resistance of the coil circuit of the delivery regulator 44, which is the opposite readjustment to that described hereinbefore in the case of acceleration.

The biasing batteries 70 and 70a are provided for the purpose of insuring that there will always be sufficient positive operating voltage on the regulator coils to operate the regulator even though it must function at times to reduce the load currents of the reel motors to very low values or actually reverse them in order to compensate for the inertia forces which may develop when the mill is rapidly accelerated or decelerated. In other words these batteries place a positive voltage bias on the regulator coil which causes the regulators to function in the required manner under any operating condition that may occur. When operating the mill with very low tensions on the strip, the amount by which the load currents of the reel motors must be reduced during periods of deceleration may be greater

than the total load currents during constant speed operation, thereby requiring an actual reversal of these currents. Such a reversal of the load currents means that the motor on the wind-up reel actually functions as a generator while the drag generator on the entry reel becomes a motor.

It is apparent that under these conditions the voltage drop across the resistors or shunts 26 and 68 in the reel motor circuits is actually reversed and without the positive biasing voltage on the regulator coils the regulators could not function to control the tensions on the strip.

It is to be understood, however, that the biasing voltage may be obtained from other sources and that the use of batteries for this purpose is merely illustrative.

In this instance the magnetizing or stationary coil 57 of the entry side regulator 45 is connected directly across conductor X or Y over a circuit which extends from conductor X in Fig. 2, conductor 89, coil 57, conductor 90 and resistor 91 to conductor Y.

Likewise the magnetizing or stationary coil 47 of regulator 44 is connected from conductor X in Fig. 3 through conductor 92, resistor 88, coil 47 and conductor 235 to conductor Y.

In order to control the excitation of the field winding 21 of the main generator, there is provided a motor-operated rheostat 93 having an operating motor 94 and a resistance element 95 disposed to be connected in series circuit relation with the field winding 21 across the excitation source through either one of two reversing switches 96 and 97.

As will be described more fully hereinafter, the generator field reversing switches 96 and 97 are operated in accordance with the direction of pass through the mill. The operation of the rheostat motor 94 may be controlled by switches 98 and 99, the closure of switch 99 being effective to energize the motor 94 in such direction as to drive the rheostat arm 100 in a direction to raise the generator voltage and switch 98 being operable to effect the opposite result.

The rheostat 93 is provided with limit switches 101 and 102 which function to deenergize the relays 98 and 99 to stop the motor when the arm 100 reaches its limit of travel.

In order to provide for increasing the generator voltage in a single step for certain purposes, as will appear hereinafter, a shunting relay 103 is provided which, when operated, short circuits a portion of the resistor 95 as shown.

The energization of the control relays 98 and 99 may be controlled by a relay 104 which is controlled in a manner to be described hereinafter.

In order to control the energization and direction of current flow through the auxiliary field 24 of the main booster generator 22, reversing switches 105 and 106 are provided. When switch 105 is closed, the field 24 is connected across the supply conductors X and Y through a variable resistor 107 and a fixed resistance 108 which is controlled by the speed selector switches 87 and 88. Resistor 107 is used to vary the voltage of the booster generator to control the stalled back tension, as will be more fully described hereinafter. The closure of switch 106 reverses the excitation of the booster generator field 24 which is the set-up for the odd pass, and connects it in series with the main resistance 108 and a second variable resistor 109. Switches 105 and 106 when closed also connect the main field 23 of the booster generator 22 directly across the

generator busses 25 and 31 through a resistor 111.

The complete control of the mill, in this embodiment of the invention, is effected through the operation of a plurality of master switches and push button switches located on both sides of the roll stand 10. With the exception of one master switch known as the pass selector which is located on the left side only, all of the other switches are duplicated in both the right and left control positions thereby providing two control stations permitting the operator to control the mill from the entry side while setting it up and later transferring his control to the wind-up side to connect up the wind-up reel and operate the mill in one direction.

In this instance, 114 is the pass selector switch having "right" and "left" operating positions. As will be described more fully hereinafter, the operation of this switch to the "left" position effects, among other things, the energization of the set-up relay 66 to establish the necessary control circuit set-ups to make an odd pass and when operated to the "right" position operates a second set-up relay 115 which makes the necessary circuit set-ups for the even passes.

As described hereinbefore, it is desirable to operate the mill at various speed ranges and in order to accomplish this, a pair of speed selector master switches 116 and 117 having "slow" and "fast" operating positions are provided, switch 116 being located on the "left" side and 117 on the "right" side of the roll stand 10. These master switches control the operation of the speed selector relays 87 and 88 in order to make the necessary circuit set-ups for the desired speed ranges.

The operation of the complete mill including the roll stand and reels after the mill has been set up and initial tension established, may be controlled by either one of two main master switches 118 and 119, switch 118 being located on the left side and 119 on the right side. These switches have "stop", "slow", "hold" and "raise" operating positions, the "stop" position being the normal non-operating position of the master switch, the "slow" position effecting the operations of the complete mill at a slow speed, the "raise" position being effective to control the relay 104 in Fig. 3, which controls the operation of the relays 98 and 99, which control the motor-operated rheostat 93. When this master switch is operated to the "raise" position, the motor-operated rheostat 93 is caused to increase the generator voltage and thereby accelerate the mill. The mill may be decelerated by operating this master switch to the "slow" position which causes the motor-operated rheostat to reduce the generator voltage. The generator voltage, and, consequently, the mill speed may be held at any desired value by operating this master switch to the "hold" position which stops and holds the motor-operated rheostat in any desired position.

Left and right reel master switches 121 and 122, respectively, are provided for individually controlling the operation of the reel motors 17 and 18. The functioning of these master switches is dependent upon the position of the set-up relays 66 and 115 so that when relay 66 is energized for the odd pass by the operation of the pass selector, switch 114, the right reel master switch 122 is rendered ineffective but since for the odd pass the set-up switch 115 is deenergized, the left reel master switch 121 is effective to control the operation of the left reel motor 18 in

order that the reel may be positioned to attach the metal strip during the set-up process for the odd pass.

In order to control the mill motor 15 separately, there are provided left and right mill master switches 123 and 124, respectively, which are utilized, as will be described more fully hereinafter, to operate the mill motor to run the metal through the rolls after back tension has been established, in order to attach the strip to the delivery reel.

In addition to the master switches, right and left inch push button switches 125 and 126 are provided for controlling the operation of the entry reel motor when setting up the mill. When inch button 125 is pressed, the right reel motor 17 is caused to rotate the reel 11 toward the mill to pay out the strip which is to be inserted between the mill rolls. Likewise, when inch button 126 is pressed, the left reel motor is caused to rotate the reel 12 toward the mill.

After the strip has been inserted between the mill rolls and the screw down mechanisms (not shown) operated to set the rolls, it is then desirable to establish a back-tension on the entry side of the mill, and it is for this purpose that push buttons 127 and 128 are provided. When push button 127 is operated, the right reel motor 17 is connected in series with the main booster generator 22 across the generator busses which causes this motor to operate in a direction to rotate the reel 11 away from the mill until the slack is taken up which causes the motor to stall. This establishes what is known as the stalled tension and when the mill is started, the metal strip is unwound from the entry reel thereby driving the entry reel motor as a generator developing sufficient torque to subject the strip to the desired back tension.

In order that a more comprehensive understanding of the features of the invention may be obtained, a description of the operation of the mill will now be set forth.

In describing the operation, it may be assumed that the main generator 19 is being driven at required speed, that the constant voltage exciter 43 is also in operation so that switches 131 and 132 may be closed to energize the conductors X and Y and also that the main booster generator 22 and the booster excitors 39 and 40 are being driven at the required speeds.

In order for the system to become operative, the low voltage relay 133 must be closed which will occur if the various control relays, push buttons and master switches are closed with exception of the pass selector switch 114, which must be operated to either the even or odd pass position before the low voltage relay may become energized.

Assuming in this instance that the pass selector 114 is operated to the odd pass position, thereby establishing an energizing circuit for the set-up relay 66 which extends from conductor X through contacts 134, bridged by segment 135, conductor 136, coil 137 of the set-up relay 66 to conductor Y. This operates the set-up relay 66 for the odd pass which at its contacts 138 completes the energizing circuit for the low voltage relay. The circuit thus established extends from conductor Y in Fig. 4 through a pair of emergency stop push buttons 139 and 140 through the closed contact members 138, conductor 141, coil of low voltage relay 133, conductor 142, closed contacts 143 and 144 of the main master switches 118, 119, conductor 145, closed contact members

146 and 147, of the mill masters 123 and 124, conductor 148, through the closed contact members of push buttons 125 to 128, inclusive, conductor 149, to point A in the cable 41, through the cable to point A in Fig. 1, conductor 151, the closed contact members 152 of a speed relay 153 associated with the reel motors 17 and 18, closed contact members 154 of a similar speed relay 155 associated with the mill motor and conductors 156 and 157 to the energized conductor X. 10

Upon the closure of the low voltage relay 133, its contacts 158 and 159 are closed to establish its own holding circuit through the closed contact member of the set-up relay 66 and the emergency stop buttons 139 and 140. The closure of contact 159 also connects conductor X to a second control conductor Z which now becomes energized. It is now evident that the master switches, push button switches and other control apparatus through which the original pick-up 20 circuit from the low voltage relay extended may now be operated to perform their other functions without deenergizing the low voltage relay.

When the pass selector 114 is operated to the odd position, it sets up, in addition to operating the set-up relay 66, certain circuits through its contact members to render the speed selector switches 116 and 117 effective to operate the speed selector relays 87 and 88. In addition to this, it energized, through its own contacts, 30 generator field contactor 97 to cause the generator 19 to develop voltage in the proper direction for the odd pass.

The circuit for operating the field switch 97 extends in Fig. 4 from conductor Z through conductor 162, contact fingers 163, bridged by the segment 164, conductor 165 to point B in the cable 42, through the cable to the point B in Fig. 2, conductor 166, the coil of relay 97, closed contact members of the other field switch 96, and conductor 167 to conductor Y. 40

In response to the closure of the set-up relay 66, the entry side regulator 45 is connected to the entry reel motor circuit which, in this case, is motor 17 and to the field winding of the auxiliary 45 booster exciter 39 which is associated with the right reel motor which is now on the entry side of the mill.

The circuit for connecting the coil of the entry side regulator 45 across the resistor 26 in the 50 circuit connecting the main booster generator and reel motor 17 across the generator busses may be traced from the upper end of the resistor 26 in Fig. 1 through conductor 168, variable resistor 12, contact members 170, bias battery 70a, resistor 69a, movable coil 59 of the regulator, conductor 172, contact members 173 and conductor 174 to the lower side of the resistor 26.

The movable contact members of the entry regulator 45 are connected to the field winding 60 of the booster exciter 39 through a circuit which extends from conductor Y in Fig. 3 through conductor 175 to the bridge circuit comprising resistors 62, 63, 64 and 65. The field winding of the booster exciter 39 is connected to opposite sides 65 of this bridge circuit through contact members 176 and 177 of the set-up relay 66 and the movable contacts 61 of the regulator connected to the bridge circuit by conductors 178 and 179.

The coil circuit of the wind-up side regulator 44 is, in this instance, connected to the wind-up reel motor 18 through a circuit which extends from upper end of resistor 68 through conductor 182, contact members 183 of the set-up relay 66, conductor 184, coil 48, conductor 185, resistor 69, 75

bias battery 70, resistance 71, contact members 186 and conductor 187 to the lower end of the resistor 68.

In this instance, conductor 188 in Fig. 3 connects conductor Y to the bridge circuit comprising resistors 52, 53, 54 and 55. The field winding of the booster exciter 40 is connected to opposite sides of the bridge circuit through conductors 188 and 190 and contact members 191, 192 of the set-up relay 66. The movable contact members of the regulator are connected across the bridge circuit and to conductor X as shown.

The proper regulator connections are now established for maintaining both front and back tension on the strip when the mill is set up and started, it being apparent that in each instance the regulators respond to the load currents flowing in the reel motor circuits to which they are connected and operate their movable contacts to continually vary the voltage impressed on the fields of the auxiliary booster excitors in such manner as to maintain the load current of the reel motor circuits substantially constant.

The closure of set-up relay 66 also operates relay 106 to connect the fields of the main booster generator 22. The energizing circuit for relay 106 extends from conductor Y in Fig. 6 through coil 195, conductor 196, closed contact members 197 of the inching relay 198, conductor 199, contact members 201 of the set-up relay 66 and conductors 202 and 227 to conductor Z.

Upon the operation of relay 106, the main field winding 23 of the booster generator 22 is connected from the generator bus 25 through conductor 203, field winding 23, resistor 111, conductor 204 to point C in the cable 41 and through the cable to point C in Fig. 4, conductor 205, contact members 206, conductor 207, to point D in cable 41 back through the cable to point D in Fig. 1 and to the opposite generator bus 31.

The energizing circuits established for the auxiliary field winding 24 of the booster 22 by the closure of relay 106 extends from conductor Y in Fig. 4 through conductor 208, contact members 209, conductor 210 to point E in the cable 41 through the cable to point E in Fig. 1, field winding 24 to point F in the cable 41 and through the cable to point F in Fig. 4, conductor 211, contact members 212, conductor 213, variable resistor 109 and speed resistor 108 to conductor X.

At this time, the closure of set-up relay 66 also operates switch 27 in Fig. 1 to connect the main booster generator 22 in series with the entry reel motor 17. The operating circuit for this switch extends from conductor Y in Fig. 1 through the coil of switch 27, to point G in the cable 41 through the cable to point G in Fig. 6, conductor 214, contacts 201 of relay 66 and conductors 202 and 227 to conductor Z.

It is now necessary to run off strip from the entry reel 11 in order that it may be inserted between the rolls of the mill 10. This requires an inching operation of the entry reel motor 17 which may be effected by the operation of the inch push button 125. The closure of the inch button to bridge its lower contact members establishes an obvious energizing circuit through the coil 215 of the inching switch 198 and closed contact members 216 of the deenergized set-up relay 115 to conductor Y.

The operation of the inching switch 198 interrupts at contacts 197 the previously completed energized circuit for the field switch 106 thereby causing this switch to drop out and disconnect the fields of the main booster generator 22. How-

ever, the opening of contacts 197 does not interrupt the previously completed operating circuit for the switch 27 and, therefore, the main booster generator is still connected in series with the entry reel motor 17.

The closure of the inching switch 198 also establishes a circuit for releasing the brake 13 on the right reel motor 17 and for operating switch 28 in Fig. 1 to complete the connection of the reel motor armature to the generator bus 31. The circuit for releasing the brake 13 extends from conductors Z in Fig. 6 through conductor 220, contact members 230, conductor 217, to point H in the cable 41, through the cable to point H in Fig. 1, conductor 218, coil of relay 219, to conductor Y. The operation of relay 219 establishes an obvious energizing circuit for the magnetic brake 13 on the reel 11.

The circuit for operating the switch 28 extends from conductor Z in Fig. 6 through conductor 221, contact members 222 of the inching relay, closed contact members 223 of relay 106, which is now deenergized, to point I in cable 41 through the cable to point I in Fig. 1 and the coil of switch 28 to conductor Y. Upon the completion of these circuits, the reel motor 17 operates to rotate the reel 11 toward the roll stand 10.

At this time also, the inching switch 198 effects the operation of a time delay relay 224 which after a predetermined time closes its contact members 225 to effect the operation of relay 103 in Fig. 3 to step up the generator voltage. The time delay relay 224 has a neutralizing winding 226 which is connected directly across the control conductors Z and Y through conductor 227, winding 226 and conductor 228 to conductor Y. The relay is also provided with a magnetizing winding 229 which is also connected across the conductors Z and Y in parallel with winding 226, which causes the relay armature to be operated to open contacts 225.

When the inching switch 198 is closed, its contact members 231 short circuit the magnetizing coil 229 thereby causing the relay to drop out after a predetermined time to close contacts 225. Upon the closure of contacts 225, the generator field step up relay 103 is operated over a circuit which extends from conductor Z in Fig. 6 through contact members 225 of the time delay relay, conductors 232 and 233 to point J in the cable 42 through the cable to point J in Fig. 3, coil of relay 103, and conductors 234 and 235 to conductor Y.

After the strip has been entered in the mill rolls, back tension may be placed on the strip by operating the tension button 127 in Fig. 6. In the meantime, however, the inch button 125 has been released and the inching switch 198 returns to its deenergized position, which again sets the brake 13 on the reel 11 and reestablishes the operating circuit for the switch 106 which reconnects the fields of the main booster generator 22 as described hereinbefore.

The operation of the tension button 127 establishes an operating circuit for the tension relay 236 which extends from conductors Z in Fig. 6 through the lower contacts of button 127, conductor 237, closed contact members 238 of set-up relay 66, conductor 239, coil of the tension relay 236 and a release tension button 241 to conductor Y.

The operation of tension relay 236 again establishes an energizing circuit for the switch 28 in Fig. 1, which was interrupted when the inch button 125 was released, which extends in this

instance from conductors Z in Fig. 6 through conductor 242, contact members 243 to point I in the cable 41 and from there on the circuit is the same as previously described. The closure of switch 5 28 connects the main booster generator armature in series with the armature of reel motor 17 across the generator buses.

The operation of tension relay 236 also again releases the brake 13, which was set when the 10 inch button 125 was released, over a circuit extending from conductors Z in Fig. 6 through conductor 242, contact members 244, on the tension relay to point K on the cable 41 through the cable to point H in Fig. 1, conductor 218, and the coil 15 of relay 219 to conductor Y.

The tension relay 236 is also provided with a contact 245 which bridges the lower contact members of the tension button 127 and obviously establishes a holding circuit for the tension relay 20 when the push button is released.

At this time, the roll stand 10 is idle, the generator 19 is developing a low voltage of possibly 50 volts while the booster generator 22 is developing a higher voltage of possibly 90 volts, thus 25 subjecting the right reel motor 17 to a voltage of possibly 40 volts in a direction to cause it to rotate away from the mill thereby taking up any slack in the strip, and then placing a stalling tension on the strip.

30 In order to complete the setting up operation of the mill, either one of the mill master switches 123 and 124 may be operated to the slow position to cause the mill motor 15 to run a sufficient length of material through the rolls for connection to the wind-up reel 12. Assuming that the operator desires to now control the mill from the left side, he may operate the mill master 123 to operate a control relay 246, which, in turn, effects the operation of the motor control switch 34 in Fig. 1 for connecting the mill motor 15 across the generator buses. The circuit for operating the control relay 246 extends from conductor Z in Fig. 5 through contact members 247, bridged by the segment 248 of master switch 40 123, conductor 249, coil of control relay 246, and conductor 251 to conductor Y.

The closure of relay 246 establishes an operating circuit for the motor control switch 34 in Fig. 1 which extends from conductor Z in Fig. 5 50 through conductor 252, contact members 253, conductor 254 to point L in the cable 41, and through the cable to point L in Fig. 1, the coil of switch 34 and conductor 255 to conductor Y.

The operation of the left mill master 123 to 55 the "fast" position establishes a shunting circuit around the magnetizing coil of time delay relay 224 which has again been picked up, which after a time interval causes this relay to close its contact members 225 to effect the operation of relay 103 to again increase the generator voltage as described hereinbefore. This shunting circuit extends from contact 256 on the mill master through conductors 257 and 258 to point 259 which obviously connects both sides of the coil 60 229 to conductor Z.

The mill is permitted to run until enough strip is run through for connection to the wind-up reel 12, whereupon the mill master 123 is operated to the "off" position to stop the mill motor 15 and maintain the back tension.

In the event that it is necessary to change the position of the wind-up reel 12 in order that the strip may be connected thereto, this may be accomplished by operation of the left reel master 70 121 in order to effect the operation of switches 75

and 33 to connect the wind-up reel motor 18 to the generator buses and release the magnetic brake 14 on the reel 12.

The operation of the reel master 121 to the "slow" position establishes a circuit for operating a second tension relay 261 in Fig. 6 similar to relay 236 which extends from conductor Z in Fig. 5 through contacts 262 of master switch 121, conductor 263, closed contact members 264 of set-up relay 115, conductor 265, coil of tension relay 261, and release tension button 266 to conductor Y.

The operation of the tension relay 261 operates switches 29 and 33, to connect the reel motor 18 to the generator circuit and establishes energizing circuit for releasing the brake 14.

The circuit for operating switch 29 in Fig. 1 extends from conductor Z in Fig. 6 through conductors 267 and 268, closed contact members 269 of relay 261 to point M in the cable 41 through the cable to point M in Fig. 1, coil of switch 29, and conductor 255 to conductor Y.

The circuit for switch 33 also extends through contact members 269 of the tension relay 261, contacts 270 of set-up relay 66 to point N in the cable 41 and through the cable to point N in Fig. 1, coil of relay 33, and conductor 255 to conductor Y.

The circuit for operating the brake 14 extends from conductor Z in Fig. 6, through conductor 215, contact members 271 of the tension relay 261, conductors 272 and 273 to point O in cable 42, through the cable to point O in Fig. 2, conductor 274, coil of relay 275 and conductor 276 to conductor Y. The operation of relay 275 establishes an obvious energizing circuit for releasing the brake 14.

The strip is now secured to the wind-up reel and the mill is completely set up for making the first, which, in this case, is the odd pass. Before 40 the mill is started, however, the speed range in which it is desired to operate should be selected by operating, in this instance, the left speed selector master 116 in Fig. 4 to either the slow or fast position, to operate relay 87 or 88, as the 45 case may be.

Assuming that it is desired to operate in the slow speed range, which means that the mill motor 15 operates at full field excitation, master switch 116 is operated to its "slow" position which 50 causes its contact segment 279 to bridge contacts 281, thereby completing an energizing circuit for the low speed relay 87 which extends from conductor Y in Fig. 4 through conductor 282, coil of relay 87, contacts 281, contacts 283 of the 55 pass selector which are now bridged by segment 284, conductor 285 to point P on cable 41, through the cable to point P in the cable in Fig. 1, closed contacts 286 on the motor switch 34 and conductor 287 to conductor X.

Attention is directed to the fact that since the energizing circuit for either one of the speed relays 87 and 88 extends through the interlock 286 on the motor switch 34, the speed range selected cannot be changed after the motor 15 has been started unless it is again deenergized to permit the switch 34 to close interlock 286. Furthermore, when the low speed relay 87 closes, its lower contacts 287 establish a holding circuit through conductor 280, closed contacts 288 of the high speed relay 88 and conductor 281. Likewise, when the high speed relay 88 is closed, by operating the speed selector 116 to the fast position, its contacts 289 establish a holding circuit through conductor 300, the normally closed 70 75

contacts 290 of the low speed relay 87 and conductor 291.

As stated hereinbefore, the operation of the speed relay 87 makes the necessary set ups and 5 circuit changes for effecting the operation of the mill in the low speed range.

Its contacts 292 close to short circuit a portion of the resistor 111 in the main field winding 23 of booster generator 22. This permits 10 the booster generator 22 to develop a high voltage for the slow speed operation when the entry reel 11 is operating at a low speed and its drag generator developing a low voltage. Its contacts 293 are closed to shunt a portion of the resistor 15 294 connected in series with the mill motor field winding 295. This subjects the motor to full field excitation. Contacts 296 are closed to render the compensating relay 74 responsive to the 20 closed position of the time delay relay 78. Upon the closure of the contacts 296, the compensating relay 74 is energized over an obvious energizing circuit which causes its contact members 74a to open and insert a block of resistance in the coil circuit of the entry side regulator 45. Contacts 74b are also closed to shunt out a portion 25 of the resistance 69 in the coil circuit of the wind-up side regulator 44. The resistances now in the coil circuits are those necessary to maintain the desired constant tension on the slow 30 speed range for constant speed operation. Closure of contact members 297 on the speed relay 87 set up the operating circuit for compensating relay 76 in order that it may be operated in response to the closure of relay 79 under conditions 35 of deceleration.

In connection with the operation of the compensating relays 74 to 77, it should be noted that in case the speed relay 88 has been closed, its contacts 298 would have caused the compensating relay 75 to be picked up instead of relay 74, which would have inserted a larger amount of resistance in the coil circuit of the entry side regulator 45 and shunted a larger amount of resistance in the coil circuit of the wind-up side 45 regulator 44. The closure of its contact members 299 would have rendered relay 77 responsive to the operation of time delay relay 79 instead of relay 76.

The closure of contacts 301 of the low speed 50 relay 87 short circuits a resistor 302 in the armature circuit of the rheostat motor 94. Should the high speed relay 88 been closed instead, its contacts 303 would have shunted a resistor 304 in the shunt field circuit of the rheostat motor 94.

Contact members 305 and 306 of low speed relay 87 also set up the proper resistances in the field circuits of the reel motors which also include the armatures of the auxiliary booster excitors 39 and 40. As shown in Fig. 4, the energizing circuit for the field winding of the reel motor 18 extends from conductor X through resistor 307, armature of auxiliary booster exciter 40 to point Q in cable 41 and through the cable 65 to point Q in Fig. 1, field winding 38 and conductor 255 to conductor Y.

The circuit for energizing the field winding of the reel motor 17 extends from conductor X in Fig. 4 through resistor 308, armature of auxiliary booster exciter 39 to point R in cable 41 through the cable to point R in Fig. 1 and field winding 37 to conductor Y.

In order that the resistors 307 and 308 may be automatically set up to the proper value depending upon the direction of pass, relays 309 and

310 are provided and controlled in accordance with the position of the set-up switch 115 which is energized only on the even pass. Since the odd pass is now being described, it is evident that contact 311 of the set-up switch 115 is closed to establish an obvious energizing circuit for relay 309, which closes its contacts 312 to shunt out a portion of the resistor 307 and it closes its contacts 313 to complete the shunting circuit set up by contacts 306 of the low speed relay 87. It will be noted that the closure of contacts 305 of the low speed relay have no effect on the resistor 307 at this time since relay 310 is deenergized. On the even passes, however, contacts 314 of relay 115 would be closed to operate relay 310 thereby 10 closing its contacts 315 to complete the shunting circuit set up by contacts 305 and contacts 316 also closed to shunt out a portion of the resistor 308. 15

The closure of low speed relay 87 also increases 20 the resistance of the energizing circuit for the auxiliary field winding 24 of the main booster generator 22 by opening contacts 317 thereby inserting a portion of resistor 108 in the field circuit. Section 318 of the resistor 108 is now shorted 25 over a circuit which extends through conductor 319, 320 to point S in cable 41, through the cable to point S in Fig. 1, through the normally closed contacts of relay 321 and conductor 157 back to the conductor X. When the relay 321 is opened 30 in response to the energization of the mill motor 15, the resistor section 318 is also inserted and the auxiliary field winding 24 of the booster generator is practically rendered ineffective because of 35 the resistance 108.

These latter connections are for the purpose 40 of rendering the auxiliary field of the main booster generator effective to establish and maintain back tension when the main generator voltage is low and therefore, does not have an appreciable effect upon the main field of the main booster generator and to render the auxiliary field winding of the main booster substantially ineffective after the mill motor starts.

After the speed range selection has been made, 45 the mill may be set in operation to roll the odd pass by operating the main master 118 to the "slow" position. The operation of this master to the "slow" position effects a number of switch operations simultaneously in order to release the 50 brake on the wind-up reel and establish the circuit connections for the mill motor 15 and wind-up reel motor 18.

The circuit for releasing the brake 14 extends 55 from conductor Z in Fig. 5 through conductor 325, contact finger 326, and segments 327, 328 and 329, contact finger 330, to point O in cable 42, through the cable to point O in Fig. 2 and conductor 274 through the coil of relay 275 as previously traced. The operation of relay 275 60 releases the brake 14.

Contact finger 331 of the main master 118 is bridged to establish a circuit for operating a running relay 332 which functions to close the connecting switches 29 and 33 for reel motor 65 18 and also a second running relay 333 to close the connecting switch 34 for the mill motor 15. The circuit for operating relays 332 and 333 extends from contact finger 331 on the main master switch through closed contacts 334 of the 70 set up relay 115, conductor 335, and through the coils of the relays in parallel to conductor Y.

Upon the closure of relay 333, its contacts 336 connects point L of the cable 41 directly to conductor Z through conductors 337 and 252 75

which again completes the previously described energizing circuit for the main motor switch 34. Its contacts 338 are closed to complete an obvious energizing circuit for the magnetizing coil 339 of time delay relay 340, which upon energization closes its contacts 341 to establish an obvious energizing circuit for a relay 342 which closes its contact members 343 to establish a parallel shunt connection across contacts 336 of relay 333. The purpose of this shunt connection is to permit relay 333 to be opened when it is desired to stop the mill without actually opening the main motor switch 34, this switch being held in until the opening of switch 342 which is controlled by the time delay relay 340. The time delay relay 340 is caused to function when the relay 333 is deenergized. This permits the roll stand to operate for a short interval after the wind-up reel has been stopped in order to provide slack in the strip.

The closure of contacts 344 of relay 332 connects points M and N on the cable 41 to conductors Z, through conductors 345 and 267, thus reestablishing the previously described energizing circuit for the connecting switches 29 and 33 of the wind-up reel motor 18. As will be recalled, this circuit was completed once before in response to the operation of the tension relay 261 controlled by the tension button 128 during the setting up operation.

Relay 332 is also provided with contacts 346 which are closed to establish an obvious holding circuit for the relays 332 and 333 which extends back through conductor 347, the closed contacts 348 of a stop relay 349 and conductor 252 to conductor Z. The stop relay 349 is energized from a circuit which extends from contact finger 351 on the main master 118 only when the main master is in the stop position, as shown, through conductor 352, closed contacts 353 of the set-up switch 115, coil of stop relay 349, and conductor 354 to conductor Y.

Relay 332 also closes its contacts 355 which are in parallel with the contacts 243 of the tension switch 236 which is now energized and, therefore, have no effect in connection with the control of switches 27 and 28 of the entry reel motor 17 at this time.

The mill is now running at slow speed in the low speed range and if it is desired to accelerate the mill, the main master switch 118 is actuated to the "raised" position to bridge contact finger 358 and establish a circuit for operating relays 104 and 99 to increase the generator voltage. The circuit thus established extends from contact finger 358 in Fig. 5, conductor 359, contacts 361, conductor 362, to point T in cable 41 and through the cable to point T in Fig. 3, conductor 363, coil of relay 104, and conductor 364 to conductor Y.

As explained hereinbefore, this effects the operation of relay 104 which closes its contacts 365 to establish an energizing circuit for the raise relay 99, which closes its contacts 366 and 367 to connect the rheostat motor 94 across the conductors X and Y so as to rotate the rheostat arm 100 in a direction to decrease the resistance of the generator field circuit. The circuit for operating the raise relay 99 extends from conductor X through contacts 365, coil of relay 99, normally closed limit switch 102 on the rheostat and conductor 235 to conductor Y. The energizing circuit for the motor 94 established by the closure of relay 99 extends from conductor Z through conductors 375 and 368, contacts 367,

armature of motor 94, contacts 301 of the low speed switch 87 which are now closed, contacts 366, and conductor 364 to conductor Y.

The motor-operated rheostat 93 will continue to raise the generator voltage until the main master switch 118 is actuated to the "stop" position which will, stop the mill or to the "slow" position which will deenergize the relay 104 thereby deenergizing the raise relay 99 and energizing at its back contacts 369 the "lower" relay 98 which will effect a reversal of the rheostat motor 94 to operate the arm 100 in the opposite direction until it is stopped by the opening of the limit switch 101 or if it is desired to hold the speed of the mill at any point the main master switch 118 may be actuated to the "hold" position which interrupts the energizing circuit for the lower relay 98 even though the relay 104 has attempted to close its circuit.

The circuits thus established for accomplishing these functions will now be described. In the event that the main master 118 is actuated to the "slow" position, the energizing circuit thus established for the lower relay 98 extends from conductor X in Fig. 5 through contacts 371 of the right main master switch 119, contacts 372 of the left main master switch 118 bridged by segment 373 to point U in cable 42 and through the cable to point U in Fig. 3, contacts 369, coil of lower relay 98, limit switch 101 and conductor 235 to conductor Y. The establishment of this circuit causes the rheostat motor 94 to operate the generator rheostat 93 in the opposite direction to reduce the voltage. This operation will continue until the motor 94 is stopped by the limit switch 101 or the operation of the main master 118 to either the "stop" or "hold" position.

In order to hold the generator voltage at any desired value when being raised or lowered the master switch may be actuated to the "hold" position. In this position its contact members 372 are not bridged by the segment 373 and, therefore, the previously traced energizing circuit for the lower relay 98 is not established and the rheostat motor 94, upon being deenergized in response to the opening of the raise relay 99, is stopped in any desired position.

As described hereinbefore, the compensating relays 74 to 77 in Fig. 2 become effective during periods of acceleration and deceleration to change the settings of the regulators 44 and 45 to compensate for the inertia forces of the reels and reel motors.

When the raise relay 99 was closed to raise the generator voltage, it also, by the closure of its contacts 374, established an energizing circuit for the magnetizing coil 83 of time delay relay 78, which controls the compensating switch 74 when operating in the low speed range. This circuit extends from conductors Z in Fig. 3, through conductor 375, contacts 374 of the raise relay, conductor 376, magnetizing coil 83, conductors 377 and 378 to conductor Y. The establishment of this circuit operates relay 78, thereby opening its contacts 85 to deenergize the compensating switch 74 which permits contacts 74a to close and 74b to open. The closure of contacts 74a decreases the resistance of the coil circuit of the regulator 45 on the entry reel motor in order to reduce the generator torque a sufficient amount to compensate for the extra tension that will be applied to the strip in accelerating the inertia of the reel and the reel motor. The opening of contact 74b increases the resistance of the coil

circuit of the regulator 44 on the wind-up side in order to cause the regulator to respond to a greater armature current and thereby produce the additional torque required to accelerate the 5 inertia of the reel and the reel motor.

When the lower relay 98 was operated to decelerate the mill, a circuit was established for operating the time delay relay 79 which controls the operation of the compensating switch 76 when 10 operating in the low speed range. The circuit thus established for the time delay relay 79 extends from conductors Z in Fig. 3 through conductor 375, contacts 379 on the lower relay 98 to point V in cable 42 through the cable to point 15 V in Fig. 2, magnetizing coil 84 and conductor 378 to conductor Y. This energizes the relay causing it to close its contacts 86, which establishes an energizing circuit for the compensating switch 76 extending from conductor X through 20 contacts 86, closed contacts 297 and the coil of switch 76 to conductor Y. Switch 76 opens contacts 76a to now increase the resistance of the coil circuit of the regulator 45 on the entry side since in this instance, the inertia forces are 25 tending to release the tension on the strip and additional back torque must be developed by the braking generator to compensate for this. This switch closes its contacts 76b to decrease the resistance of the coil circuit of the regulator 45 on the delivery side, since in this instance the inertia forces are acting so as to increase the tension and, therefore, the torque developed by the reel motor must be reduced a corresponding amount. It is to be 30 understood that during the decelerating periods 35 the compensating switch 74 is energized and contacts 74a open and 74b closed.

When it is desired to stop the mill at the end of the pass, the main master switch 118 is actuated to the "stop" position, as shown. At this 40 time, contact finger 330 is disengaged which interrupts the circuit of the brake relay 275 which opens to deenergize the brake 14 on the delivery reel.

When the main master switch 118 was actuated 45 to the "stop" position, relay 333 is deenergized and opens its contact 336. However, since these contacts are bridged by contacts 343 of the relay 342, the energizing circuit for the main motor switch 34 is not interrupted. The opening of contacts 338, however, on switch 333 deenergizes 50 the magnetizing coil of time delay relay 340 thereby causing this relay to open its contact 341 after a predetermined time to deenergize relay 342 which thereupon opens its contacts 343 to interrupt the energizing circuit for the main 55 motor switch 34.

The relay 332, however, was deenergized immediately upon the actuation of the master switch to the "stop" position and opened its contacts 344 to interrupt the operating circuit for the reel 60 motor switches 29 and 33. It is, therefore, apparent that the wind-up reel 12 was stopped slightly in advance of the stopping of the main rolls in order to provide sufficient slack in the strip to 65 prevent injury thereto.

The mill is now stopped with back tension still being applied by the entry reel 11. Back tension is still applied because of the fact that the pass selector switch 114 is still in the odd pass position which maintains the set-up relay 66 closed. 70 As will be recalled, this set-up relay was closed before the right reel 11 was inched to set up the mill and later its motor connected in series with the main booster generator to establish back tension. After this back tension has once been 75

established, it is maintained until the set-up relay 66 is released.

In order now to reverse the mill for the even pass, the pass selector switch 114 must be actuated to the even pass position which deenergizes the set-up relay 66 for the odd pass and energizes the set-up relay 115 for the even pass.

When the set-up relay 66 is deenergized, it drops open to close all of the back contacts which function to reverse the regulator connections to the booster excitors 39 and 40 and the circuits of the reel motors 17 and 18. That is, the regulator 45 is now used on the opposite side which becomes the entry side of the mill and its coil 59 is connected across the resistor 26 in the main booster generator circuit in the opposite direction through back contacts 170a and 173a. The contact members 51 of the regulator 44 are now connected to the field winding of the auxiliary booster exciter 40 through back contacts 192a 20 and 191a. Likewise, the coil 49 of the regulator 44 is now connected across the resistor 67 in the armature circuit of the reel motor 17 through back contacts 183a and 186a.

Back contacts 385 of the set-up relay 66 in Fig. 5, are closed to render the tension relay 236 responsive to the operation of the right reel motor master switch 122 and its back contacts 386 are closed to energize the booster generator switch 30 in Fig. 1 to connect the armature of the reel motor 18 in series with the main booster generator 22 in order that this motor may now become the drag generator. This circuit extends from conductor Z in Fig. 6 through conductors 221 and 202, back contacts 386, conductor 387, 35 to point X in the cable 41 and through the cable to point X in Fig. 1, coil of booster switch 30 and conductor 255 to conductor Y.

Back contacts 386 of set-up relay 66 also establish a circuit for operating relay 105 to reverse the connection of the auxiliary field 24 on the main booster generator. This circuit extends from contacts 386 through conductor 388, closed contacts 389 on the inching switch 390, conductor 391 and coil of relay 105 to conductor Y. Contacts 206a on the relay 105 also connect the main field 23 of the booster generator 22 across the generator buses.

When the set-up switch 115 is closed, its contacts 311 are opened to interrupt the energizing circuit for switch 309 and its contacts 314 closed to establish an energizing circuit for switch 310, which effects a readjustment of the resistors 307 and 308 in the auxiliary booster exciter circuits. Contacts 353, 361 and 334 are opened to render the left main master 118 ineffective and contacts 353a, 361a and 334a are closed to render the right main master switch 119 effective to control the operation of the mill. The circuits closed by the operation of the master switch 119 are otherwise the same as described hereinbefore in connection with the odd pass operation.

The speed selector master switch 117 on the right side would now be used instead of master switch 116 and assuming that operation in the low speed range was desired, its operation to this position would operate the speed relay 87 to set up exactly the same circuits as described hereinbefore for the odd pass.

Before the even pass may be made, it is again necessary to establish tension on the entry side of the mill. This may be accomplished by the operation of the tension push button 128 which establishes a circuit from conductors Z through the lower contacts of push button 128, conductor 75

386, closed contacts 387 of the set-up relay 115, conductor 388, coil of tension relay 261 and tension release push button 266 to conductor Y.

The closure of contacts 269 on tension relay 5 261 again complete the previously traced energizing circuit through the point M on cable 41 and through the cable to point M in Fig. 1 for the switch 29, but switch 33 is not closed in this instance because contacts 270 of the set-up relay 10 66 are now open. The operation of the switch 29 completes the connection of the armature of the reel motor 18 and main booster generator 22 to the generator buses.

At this time, the generator is again developing 15 possibly 50 volts in the opposite direction while the booster is developing a higher voltage possibly 90 volts thereby subjecting the reel motor 18 to approximately 40 volts tending to rotate it away from the mill and establish back tension 20 on the strip in the same manner as described in connection with reel motor 17 for the odd pass. The tension relay 261 also closes its contacts 271 to again establish the previously traced operating 25 circuit for the brake 14 on reel 12. It also closes an interlock 389 to establish an obvious holding circuit in order that it may be held energized when the tension push button 128 is released.

The operation of the mill from this point on 30 for the even pass is controlled by the master switch 119 over the circuits which have been set up by the opening of the set-up relay 66 and the closure of the opposite set-up relay 115.

Operation of the main master switch 119 to 35 the slow position sets the mill in operation at its minimum speed in the same manner as described in connection with the odd pass. Acceleration of the mill is effective by operating the master switch to the "raise" position and to the "hold" 40 position if it is desired to maintain any particular speed. Since these circuits have already been described in detail in connection with the odd pass, it is deemed to be unnecessary to repeat the description.

45 It may be stated in conclusion, that, while the illustrated example constitutes a practical embodiment of my invention, we do not wish to limit ourselves strictly to the exact details herein illustrated, since modifications of the same 50 may be made without departing from the spirit of the invention, as defined in the appended claims.

We claim as our invention:

1. In a rolling mill, winding and unwinding 55 reels for handling strip material being worked by the mill, dynamo-electric machines for driving the reels, a power source, a booster generator, and means whereby either of said dynamo-electric machines may be connected to the power 60 source to operate as a motor and the other connected to the power source in series with the booster generator to operate as a braking generator to tension the material, as it is being worked by the mill.

65 2. The combination with a rolling mill for rolling strip material having winding reels disposed on opposite sides thereof for winding up and unwinding the strip, of a motor for driving the 70 rolling mill, a source of power, a motor for driving one of said reels to wind up the strip, a braking generator having driving connection with the other reel for exerting a tension on the unwinding strip, and a booster generator having an armature connected in series with the braking 75 generator armature for causing the braking gen-

erator to return energy to the power source regardless of its speed of operation.

3. The combination with a rolling mill and winding and unwinding strip-handling reels located on opposite sides thereof, of a dynamo-electric machine connected to each reel disposed to function as a driving motor or a regenerative brake therefor, a source of power and a booster generator connected in series circuit relation with the dynamo-electric machine which serves as the 10 regenerative brake to the power source in such manner that their voltages are added whereby said dynamo-electric machine may regenerate power without developing a voltage as high as that of the source.

4. The combination with a roll stand and winding reels positioned on opposite sides of the roll stand for subjecting the material being rolled to tension on both sides of the roll stand, of a motor for driving the roll stand, motors for driving the 20 reels, a generator for supplying power to said motors, a booster generator, means for connecting the roll stand motor and one reel motor to the power source, means for connecting the other reel motor to the power source in series with the 25 booster generator, and means including a regulator for each reel motor for controlling the excitation of the reel motors to maintain predetermined tensions on the material passing through the roll stand.

5. In combination, a stand of reducing rolls, a main motor for driving the reducing rolls, winding reels on opposite sides of the roll stand for passing strip material back and forth through the roll stand, dynamo-electric machines for 35 driving the reels, a source of power, a booster generator, means operable to alternately connect one dynamo-electric machine and the main motor to the power source and the other dynamo-electric machine to the power source in series 40 with the booster generator, whereby the dynamo-electric machines on the reels alternately function as motors and back-tension generators to maintain tension on the strip material as it passes back and forth through the reducing rolls, and means associated with each dynamo-electric 45 machine and operable in response to the load currents thereof to cause said machines to maintain substantially constant tension on the material.

6. In combination, a stand of reducing rolls, a main motor for driving the reducing rolls, winding reels on opposite sides of the roll stand for passing strip material back and forth through the roll stand, dynamo-electric machines for 55 driving the reels, a source of power, a booster generator, means operable to alternately connect one dynamo-electric machine and the main motor to the power source and the other dynamo-electric machine to the power source in 60 series with the booster generator, whereby the dynamo-electric machines on the reels alternately function as motors and back-tension generators to maintain tension on the strip material as it passes back and forth through the reducing rolls, and means including a current regulator associated with each dynamo-electric machine operable to regulate the excitation of 65 said machines to maintain a substantially constant tension on the strip material as it passes back and forth through the roll stand.

7. In an electric drive for a rolling mill provided with a roll stand and a winding reel on either side thereof, in combination, a motor for driving the roll stand, a motor for driving each 75

winding reel, a source of variable voltage power for the motors, means for connecting the roll stand motor and one of the reel motors to the power source, a booster generator, and means for connecting the booster generator in series with the other reel motor across the power source, whereby said reel motor may be operated as a drag generator at a voltage less than the power supply voltage and return energy to the power source.

8. In combination, a roll stand for working strip material, a main motor for driving the roll stand, winding reels on opposite sides of the roll stand, dynamo-electric machines connected to said reels, a source of variable voltage power, a booster generator disposed to be connected in series with either one of said dynamo-electric machines across the power source, means operable to connect either one of the dynamo-electric machines directly across the power source to rotate the reel toward the roll stand while the roll stand is in a non-operating condition, means operable to connect either one of the dynamo-electric machines across the power source in series with the booster generator to cause said dynamo-electric machine to function as a motor to rotate the reel away from the roll stand to exert a back tension on the material before the roll stand is set in operation, and means operable to connect the other dynamo-electric machine and the main motor across the power source to start the mill stand, whereby the reel driven by said other dynamo-electric machine is caused to subject the strip material to a pulling tension as it comes through the roll stand and the other reel is caused to drive the dynamo-electric machine in series with the booster as a generator to exert a back tension on the material.

9. The combination with a roll stand and winding reels on opposite sides of the stand adapted to alternately wind and unwind material being passed through and worked by the roll stand, a main motor for driving the roll stand, motors connected to each reel adapted to alternately function as generators and motors dependent upon the direction in which the material is moving through the roll stand, a booster generator, a power source, means operable to connect the booster generator in series with the motor on the unwinding reel across the power source, said motor then functioning as a drag generator when the roll stand is operated, means operable to connect the main motor and the winding reel motor to the power source to effect a rolling operation, a source of excitation for the reel motors, a booster exciter connected in series with the field winding of each reel motor across the excitation source, and regulators responsive to the load currents of their respective reel motors for controlling the excitation of the booster excitors and thereby the excitation of the reel motors to maintain predetermined constant tensions on the material between each reel and the roll stand during rolling operations.

10. The combination with a roll stand and winding reels on opposite sides of the roll stand disposed to alternately wind and unwind material being passed through and worked by the roll stand, a main motor for driving the roll stand, motors connected to each reel adapted to alternately function as generators and motors dependent upon the direction in which the material is moving through the roll stand, a booster generator, a power source, means operable to connect the booster generator in series with the

motor on the unwinding reel across the power source, said motor then functioning as a drag generator when the roll stand is operated, means operable to connect the main motor and the winding reel motor to the power source to effect a rolling operation, a source of excitation for the reel motors, a booster exciter connected in series with the field winding of each reel motor across the excitation source, regulators responsive to the load currents of their respective reel motors for controlling the excitation of the booster excitors and thereby the excitation of the reel motors to maintain predetermined constant tensions on the material between each reel and the roll stand during rolling, means operable to change the speed of the main motor and the motor on the winding reel, and means responsive to the operation of said speed changing means for changing the characteristics of the regulators to compensate for the inertia forces of the reels and reel motors so that tension on the material will not be varied during periods of acceleration and deceleration.

11. In an electric drive for a rolling mill comprising a roll stand and winding reels on opposite sides thereof adapted to alternately wind and unwind strip material being worked by the roll stand, in combination, a main motor for driving the roll stand, a dynamo-electric machine connected to each reel disposed to alternately function as generators and motors dependent upon the direction of movement of the strip through the roll stand, a variable voltage generator for supplying power to the main motor and dynamo-electric machines, a booster generator, means for connecting the booster generator in series with the unwinding reel-dynamo-electric machine across the generator to cause the unwinding reel to exert a back tension on the strip, means including a master controller operable to one position to connect the main motor and the dynamo-electric machine on the winding reel to the generator to cause the strip material to be unwound from the unwinding reel against the drag of the dynamo-electric machine and passed through the roll stand under a back tension while subjected to a pulling tension by the winding reel, and means responsive to the operation of the master controller to a second position for increasing the generator voltage and to the first position for lowering the voltage and to a third position for holding the generator voltage at any desired value.

12. In combination, a roll stand, winding reels on opposite sides of the roll stand disposed to alternately wind and unwind strip material passing alternately in opposite directions through the roll stand, a motor for driving the roll stand, motors connected to drive each reel, a generator provided with a field winding for supplying power to the motors, a main booster generator, a source of constant potential excitation, reversing switches for connecting the generator field winding to the excitation source in opposite directions, a motor-operated rheostat for controlling the excitation of the generator, switches operable to connect the main motor to the generator, switches operable to connect the reel motors directly across the generator or either one across the generator in series with the booster generator, whereby the motor connected directly across the generator functions as a winding motor and the other connected in series with the booster functions as a drag generator when the material is unwound from its associated reel, means including a cur-

rent regulator disposed to be associated with each reel motor for controlling its excitation to maintain constant tension on the material being wound and unwound, means including a master switch selectively operable to select the direction of the pass through the roll stand by effecting the operation of the proper reversing switches for the generator field winding and connecting the means including the regulators to the reel motor circuits and their field winding circuits, and a main master switch operable to a plurality of positions to start, stop and vary the speed of the mill, said main master switch being operable to a "slow" position to close the main motor switches and the switches connecting one reel motor directly to the generator and the other reel motor to the generator through the booster generator depending on the direction of the pass, and to a "raise" position to cause the motor-operated rheostat to raise the generator voltage and change the regulator settings to compensate for inertia forces of the reels and reel motors during acceleration, and back to "slow" position to cause the motor-operated rheostat to lower the generator voltage and to change the regulator settings to compensate for the inertia forces of the reels and reel motors during deceleration or to a "hold" position to cause the motor-operated rheostat to hold the voltage at a predetermined value, or to a "stop" position to stop the mill.

13. The combination, with a rolling mill for rolling strip material and winding and unwinding reels on opposite sides thereof, of a motor connected in driving engagement with each reel to alternately function as motors to place a tension on the strip material as it leaves the mill and as regenerative braking generators to place a tension on the material as it enters the mill, each of said reel motors being provided with a field winding connected across a constant voltage power source, a booster exciter generator connected in series with each field winding to vary the voltage impressed thereon, a pair of current regulators for controlling the excitation of the booster exciter generators, means operable to connect one regulator to the circuit of the motor driving the winding up reel and its associated booster exciter generator and the other regulator to the braking generator and its associated booster exciter generator, said means having a normal position which connects the regulators to the motors in opposite relation thereby to always use one regulator on the winding up reel motor and the other on the unwinding reel motor, and means associated with each current regulator for changing its normal adjustment for different speed ranges of operation of the mill and during periods of acceleration and deceleration of the mill, whereby the tension in the strip on both sides of the mill is maintained constant for all mill speeds and regardless of the inertia forces of the reels and their motors during periods of acceleration and deceleration of the mill.

14. In combination, a rolling mill for rolling strip material, a motor for driving the mill, winding and unwinding reels on opposite sides of the mill for handling the strip material, motors connected to the reels, a generator for supplying power to mill and reel motors, a booster generator disposed to be connected in series with the reel motor on the entry side of the mill, said reel motor then functioning as a braking generator to tension the strip on the entry side, means operable to connect the booster generator and either reel motor in series across the generator to subject the

strip to a back tension, means operable to connect the other reel motor and mill motor across the generator circuit to start the mill and cause the reel on the delivery side of the mill to likewise exert a tension on the strip, means including a current regulator for controlling the excitation of each reel motor, said regulators having operating coils connected to their associated reel motor circuits through resistors to be energized in accordance with the load currents, the resistors being normally adjusted to cause the regulators to maintain constant load currents to maintain constant tension on the strip for constant speed operation, control means for raising and lowering the main generator voltage to accelerate and decelerate the mill, means responsive to the operation of said control means to raise the generator voltage and accelerate the mill for increasing the resistance of the coil circuit of the regulator on the wind-up reel motor and for simultaneously decreasing the resistance of the coil circuit of the regulator on the entry reel generator, and means responsive to the operation of the control means to decelerate the mill for changing the resistances of the regulator coil circuits in the opposite manner.

15. In combination, a rolling mill for rolling strip material, a motor for driving the mill, a reel for holding the strip material to be unwound from the reel by the mill, a generator connected to said reel disposed to function as a regenerative brake, a main generator for supplying power to the mill motor, said reel generator being connected to the main generator, means including a current regulator for controlling the reel generator excitation to control the tension of the strip in accordance with the load current of the reel generator, said regulator being adjusted to maintain a predetermined constant generator current corresponding to the strip tension desired, means operable to vary the main generator voltage to accelerate and decelerate the mill motor, and means responsive to said means operable to change the regulator adjustment during the accelerating and decelerating periods to permit an increase in the generator current during deceleration to compensate for the inertia of the reel and generator and a decrease in generator current during acceleration to compensate for the inertia of the reel and generator.

16. In combination, a rolling mill for rolling strip material, a motor for driving the mill, a reel for holding the strip material to be unwound from the reel by the mill, a generator connected to said reel disposed to function as a regenerative brake, a main generator for supplying power to the mill motor, said reel generator being connected to the main generator, means including a current regulator for controlling the excitation of the reel generator, said regulator having an operating coil energized through a resistor in accordance with the reel generator current and the resistor normally adjusted to maintain a predetermined constant tension on the strip during constant speed operation of the mill, control means for varying the main generator voltage to accelerate and decelerate the mill to different speeds, means responsive to the operation of the control means to accelerate the mill for decreasing the resistance of the regulator coil circuit, and means responsive to the operation of the control means to decelerate the mill for increasing the resistance of the regulator coil circuit, thereby to compensate for the additional braking inertia force in the first instance and the additional

overhauling inertia force in the second instance.

17. The combination with a mill stand for rolling strip material and a reel for holding the strip material, of a main motor for driving the roll stand to unwind the material from the reel, a source of power for the motor, a generator connected to the reel, a booster generator connected in series with the generator to the power source, means including a regulator responsive to the generator load current for controlling the excitation of the generator to control its torque and consequently the tension on the material as it is unwound from the reel, means for varying the voltage of the power source to accelerate or decelerate the main motor and mill stand, means responsive to the operation of said means to accelerate the main motor for changing the adjustment of the regulator to reduce the generator torque and means responsive to the operation of said voltage varying means to reduce the speed of the main motor for changing the adjustment of the regulator to increase the generator torque.

18. The combination with a motor-driven roll stand disposed to be operated at different speeds, 25 winding reels on opposite sides thereof for alternately winding up and unwinding material being worked by the roll stand, of motors for operating the reels, means including a regulator associated with each motor for controlling the 30 excitation of the reel motors, said regulators having operating coils energized in accordance with the voltage drop across a portion of their respective motor circuits, a resistance in series with each coil, means for varying the value of said 35 resistances to cause the regulators to maintain a predetermined excitation corresponding to the desired constant tension to be placed on the material, means for varying the speed of the motor-driven roll stand, and means responsive to the 40 operation of said speed varying means for increasing the resistance of regulator coil circuit associated with the winding reel and for decreasing the resistance of the coil circuit of the regulator associated with the unwinding reel when 45 the speed of the roll stand is increased and for varying the resistance of said regulator coil circuits in the opposite manner when the speed of the roll stand is being decreased.

19. In combination, a rolling mill, means for 50 driving the mill, winding reels positioned on opposite sides of the mill for winding and unwinding strip material passing through the mill, motors connected in driving engagement with the reels disposed to alternately function as reel 55 driving motors and reel braking generators to subject the strip material to pulling and back tensions, means including a regulator for controlling the excitation of each reel motor to maintain the tensions substantially constant, said 60 regulators having operating coil circuits energized in accordance with the load currents of the reel motors, and means for subjecting the coil circuits of the regulators to a substantially constant biasing voltage, thereby to maintain a positive 65 operating voltage on the regulator coil, regardless of the amount and direction of flow of the load currents of the reel motors.

20. In combination, a work device, means for 70 driving the work device, a reel for holding material to be worked by said work device, a dynamo-electric machine connected to the reel and disposed to be driven thereby as a regenerative brake when the material is being unwound from the reel by the work device to subject the material to a back tension, means including a regu-

lator for controlling the excitation of the dynamo-electric machine to control the back tension on the material, said regulator having an operating coil subjected to a voltage proportional to the load current of the dynamo-electric machine, 5 and a source of constant voltage connected to the regulator coil, thereby to provide for maintaining a positive voltage on the regulator coil regardless of the direction and amount of the voltage determined by the load current.

21. The combination with a rolling mill and winding and unwinding reels on opposite sides thereof, of a dynamo-electric machine connected to each of said reels adapted to serve as a driving motor or as a regenerative brake therefor, a 15 source of power, a booster-generator, and means operable to connect the booster-generator across the power source in series circuit relation with the dynamo-electric machine functioning as the regenerative brake to cause the voltages developed by each to be added, whereby said dynamo-electric machine may regenerate power at a 20 lower voltage than the source into which it regenerates.

22. In combination, a reel for holding strip 25 material, means for unwinding the material from the reel, means operable to vary the speed of the unwinding means to accelerate and decelerate the reel, a generator connected to be driven by the reel to subject the reel to a retarding force 30 and thereby tension the material being unwound therefrom, means including a regulator for controlling the excitation of the generator to control the retarding force developed by the generator, said regulator being disposed to maintain the load current of the generator at a substantially constant predetermined value, and means responsive to the operation of the means 35 for varying the speed of the unwinding means for varying the adjustment of the regulator, 40 thereby to maintain a substantially constant tension on the material regardless of the speed of the unwinding means and during periods of acceleration and deceleration of the reel.

23. The combination with a rolling mill having 45 winding reels on opposite sides thereof for handling strip material being worked by the mill, a source of power, variable-speed means for driving the mill, a motor for driving each reel, means operable to selectively connect either one 50 of the reel motors to the power source to function as a motor to drive its associated reel in a direction to tension the material as to comes from the mill and to connect the other motor to the power source to function as a generator 55 driven by its associated reel and the material being unwound from said reel by the mill, a booster-exciter for controlling the excitation of each reel motor, and regulator means independent of the material for controlling the excitation 60 of the booster exciter to automatically maintain predetermined tensions on the material on both sides of the mill regardless of the mill speed and the speed of the reel motors.

24. In combination, a roll stand for working 65 strip material, winding reels on opposite sides thereof for handling the material, a source of power, means for driving the roll stand at different speeds, dynamo-electric machines connected to the reels adapted to alternately function as motors receiving power from the source and as braking generators returning power to the power source dependent upon the direction of operation of the roll stand, electro-responsive means for controlling the excitation of each 70 75

dynamo-electric machine, and regulator means associated with each dynamo-electric machine for controlling the operation of the electro-responsive means to maintain the load currents of the dynamo-electric machine substantially constant at predetermined values, thereby to subject the material to a substantially constant tension regardless of the speed of the roll stand.

25. The combination with a motor-driven rolling mill disposed to be operated at different speeds and motor-operated winding reels on opposite sides thereof for alternately winding up and unwinding material being worked by the rolling mill, of a source of power, means operable to connect the mill motor and one reel motor to the power source to unwind material from one reel and wind it upon the opposite reel, means for connecting the unwinding reel motor to the power source to function as a braking generator to exert a back tension on the material, regulator means for controlling the excitation of the reel motors to maintain a predetermined constant tension on the material on both sides of the mill, and means operable to vary the operating characteristics of the regulator means in accordance with the different speeds of the mill, thereby to provide for maintaining substantially constant tensions on the material regardless of the mill speed.

30. 26. In combination, a work device, means for driving the work device, a reel for holding and unwinding material to be worked by the work device, a dynamo-electric machine connected to be driven by the reel as a regenerative braking generator as the material is unwound therefrom by the work device, a source of excitation voltage for the braking generator, a booster exciter for controlling the excitation voltage of the braking generator, and regulator means for controlling the excitation and voltage of the booster exciter in accordance with the load current of the braking generator, thereby to cause the braking generator to subject the material to a substantially constant back tension regardless of the speed of the work device.

35. 27. In combination, a work device, a motor for driving the work device, a source of power for the motor, a reel for holding material to be worked by the work device, a dynamo-electric machine connected to the reel disposed to be driven thereby as a regenerative brake to tension the material as it is unwound by the work device, means for varying the voltage of the power source to vary the speed of the mill, and a booster-generator connected in series circuit relation with the dynamo-electric machine to the power source and disposed to develop a voltage in the same direction as the dynamo-electric machine, whereby the dynamo-electric machine may return energy to the power source while developing voltages lower than the voltage of said power source.

40. 28. In combination, a work device, a motor for driving the work device, a source of power for the motor, a reel for holding material to be worked by the work device, a dynamo-electric machine connected to the reel disposed to be driven thereby as a regenerative brake to tension the material as it is unwound by the mill, means for varying the voltage of the power source to vary the speed of the mill, a booster-generator connected in series with the dynamo-electric machine to the power source, said booster-generator having its excitation and voltage varied in accordance with the change in voltage of the power source and

being disposed to develop a voltage in the same direction as that of the dynamo-electric machine whereby the dynamo-electric machine may return energy to the power source while developing lower voltages than that of the power source, and means for controlling the excitation of the dynamo-electric machine to automatically maintain a predetermined constant load current and thereby a predetermined constant back tension on the material being worked.

45. 29. In combination, a work device, a motor for driving the work device, winding reels on opposite sides of the work device for alternately winding and unwinding material to be worked by the work device, a motor for driving the work device, a variable voltage source of power for the motor, a dynamo-electric machine connected in driving relation to each reel and disposed to alternately function as reel driving motors and reel braking generators depending upon the direction of operation of the work device, means including a regulator for controlling the excitation of each of the dynamo-electric machines in accordance with the load currents of their respective machines to maintain predetermined substantially constant tensions on the material on both sides of the work device, and means for causing the regulators to function to maintain the substantially constant predetermined tension regardless of the direction and amount of current flow in the dynamo-electric machines.

50. 30. In combination, a work device, a motor for driving the work device, winding reels on opposite sides of the work device for alternately winding and unwinding material to be worked by the work device, a motor for driving the work device, a variable voltage source of power for the motor, a dynamo-electric machine connected in driving relation to each reel and disposed to alternately function as reel driving motors and reel braking generators depending upon the direction of operation of the work device, means including a regulator associated with each dynamo-electric machine for controlling the excitation thereof to maintain their load currents at substantially constant predetermined values, said regulators having operating coils energized in accordance with the load currents of their respective dynamo-electric machines, and a source of constant voltage connected in circuit with the operating coil of each regulator, thereby to subject each regulator to a biasing voltage of sufficient magnitude as to maintain the voltage on their operating coils in the same direction regardless of the direction of flow and amount of their respective load currents.

55. 31. The combination with a rolling mill and a winding reel for holding material to be worked by the mill, of a motor for driving the mill, a source of variable voltage power for the mill motor, means for varying the voltage of the power source to vary the speed of the mill motor, a dynamo-electric machine connected to be driven as a regenerative brake by the reel as material is unwound therefrom by the mill, means including a regulator for controlling the braking torque developed by said dynamo-electric machine, and means responsive to the operation of the means for varying the voltage of the source for controlling the functioning of the regulator so as to cause the dynamo-electric machine to develop less braking torque when the mill is accelerated and more braking torque when it is decelerated.

60. 32. In combination, a work device, means for

driving the work device, a reel for holding and unwinding material to be worked by the work device, a generator disposed to function as a brake for the reel to subject the material to a tension, 5 a source of variable-voltage power for controlling the speed of the work device, a booster-generator connected in series with the braking generator across the variable voltage power source in such manner that their voltages are additive, 10 said booster generator being disposed to develop a voltage proportional to the voltage of the power supply, and regulator means operable to maintain the load current of the braking generator substantially constant, whereby the braking generator 15 may return energy to the power source while developing a voltage of lower value than that of the power source.

33. In combination, a work device, a motor for driving the work device, a reel for holding material to be worked by the work device, a source of power for the motor, means for varying the voltage of the power source to vary the speed of the motor, a braking generator for the reel, a booster-generator having its field energized in accordance with the voltage of the power source and its armature connected in series with the armature of the braking generator across the power source in such manner that their respective voltages are additive, and a current regulator for controlling 30 the excitation of the braking generator to maintain a substantially constant load current and terminal voltage, thereby to maintain a constant tension on the material regardless of the speed of the work device or diameter of the reel.

34. A control system for apparatus having an element operating on a strip of material comprising a pair of dynamo-electric machines connected to the strip, a supply source, circuit connections between said source and said machines, 40 means for introducing an additional voltage into the circuit of one of said machines and said source and means controlling said voltage in accordance with the operation of said element.

35. A control system for apparatus operating on a strip of material comprising a pair of dynamo-electric machines mechanically connected to the strip, a source of variable voltage, circuit connections from said source to said machines, and means for introducing into the circuit of 45 said source and one of said machines a voltage proportional to the voltage of said source.

36. A motor control system comprising in com-

bination, a main motor for driving a load, a pair of dynamo-electric machines connected to said load, a source of supply, separate circuit connections from said source to said motor and each of said dynamo-electric machines, means for controlling the direction of rotation of said motor and for effecting operation of one of said machines as a generator and the other as a motor when said main motor is rotating in one direction and for reversing the operations of said machines 10 when said motor is rotating in the opposite direction, a second generator, and means for selectively connecting said second generator in the circuits of said dynamo-electric machines in accordance with the direction of rotation of said 15 main motor.

37. A control system for rolling mill apparatus and the like having an element for reducing the thickness of a strip of material and having winding and unwinding reels comprising a motor for 20 driving said element, a pair of dynamo-electric machines, one connected to each of said reels, supply means for said motor and dynamo-electric machines, and means for extending the speed 25 range of the unwinding reel machine beyond that obtainable with field control comprising a second generator connected between said unwinding reel machine and its source so that the voltage of said second generator adds to the voltage 30 of said unwinding reel machine.

38. A control system for strip rolling mill apparatus having a pair of main rolls and winding and unwinding reels comprising in combination, a pair of dynamo-electric machines, one connected to each of said reels, a source of supply for 35 said dynamo-electric machines, control means providing operation of the unwinding reel machine as a generator and the winding reel machine as a motor, a means for extending the operating range of said machines beyond that obtainable with field control comprising a generator 40 provided with a main field winding energized in accordance with the speed of the strip and having its armature connected in the circuit of said unwinding reel machine so that its voltage 45 adds to the voltage of said machine, and an auxiliary field winding on said generator excited for energizing said unwinding reel machine to exert a tension on the strip when the mill is stalled.
